UNITED STATES PATENT OFFICE.

JOHN C. RINGE, OF STRATFORD, CONNECTICUT, ASSIGNOR TO THE SINGER MANUFACTURING COMPANY, OF ELIZABETH, NEW JERSEY, A CORPORATION OF NEW JERSEY.

TRIMMING MECHANISM FOR SEWING MACHINES.

Application filed August 8, 1924. Serial No. 730,801.

This invention relates to improvements in trimming mechanisms for sewing machines and has for its primary object to provide a trimming mechanism in which a reciprocating trimmer blade performs its work-severing action during the effective action of the work-feeding means.

More specifically, the present invention has for an object to provide a sewing machine having continuously effective work-feeding means with trimming mechanism of the reciprocating-blade type, which trimming mechanism is preferably capable of being thrown into and out of effective action during the operation of the machine.

Another object of this invention is to provide a needle-feed machine, i. e., a machine wherein the endwise reciprocating needle has a lateral movement in the line of seam-formation while in the work, with a trimming mechanism of the reciprocating-blade type which is effective to sever the work during the lateral feeding movement of the needle.

Other objects of the invention will be apparent from the following description and claims.

The present improvement has been embodied in a continuous-feed sewing machine substantially as disclosed in the U. S. Patent to H. Corral and B. A. Stevens, No. 1,414,625, May 2, 1922, wherein the work is continuously advanced past the stitch-forming mechanism. The improvement comprises a trimming mechanism of which the trimmer-blade has a cutting-edge disposed to reciprocate in a plane substantially parallel with the line of seam-formation. The trimmer-blade is carried by a trimmer-bar 40 slidingly mounted for endwise reciprocation upon the swinging needle-bar frame, whereby during its work-severing action the trimmer-blade is vibrated laterally in timed relation with respect to and in the direction of the advancing movement of the work, i. e., in unison with the advance of the work. To reciprocate the trimmer-bar, it is releasably connected with mechanism operated from the needle-bar reciprocating shaft and when disconnected from its actuating mechanism the trimmer-bar is raised by a spring into an inoperative position.

In the accompanying drawings, Fig. 1 is a longitudinal sectional view of a sewing machine in which the present improvement

has been embodied. Fig. 2 is an end view of the needle-head of the machine with the face plate removed.

Fig. 3 is a longitudinal section of the head of the overhanging bracket-arm of the sewing machine.

Fig. 4 is a perspective view of the trimming mechanism. Fig. 5 is a plan view of the throat-plate.

Referring to the drawings, the sewing machine shown is provided with a bed-plate 1, the upper surface of which serves as a cloth-plate. Rising from the bed-plate is the hollow standard 2, curving laterally into the overhanging arm 3 terminating in the head

4. Suitably journaled in the overhanging arm is the main or needle-reciprocating shaft 5 carrying at one end the belt-wheel 6 and at its opposite end the shaft-flange 7, provided with a crank-pin 8. Embracing the crank-pin 8 is the apertured and laterally offset end of the link 9 of which the opposite end is connected in a like manner with the stud 10 projecting from the collar 11 suitably clamped upon the needle-bar 12.

The needle-bar 12 carries the needle 13 and is journaled for vertical reciprocation in spaced bearings, as 14, provided in the swinging frame 15 pivotally supported at its upper end upon the stud 16 secured in the head 4. In order to impart swinging movements to the frame 15, the lower of the spaced bearings 14 is suitably connected with a crank-arm 17 on one end of the rock-shaft 18, journaled in bearings provided in the overhanging arm. The rock-shaft 18 is disposed substantially parallel to the driving shaft 5 and has secured thereupon the forked arm 19 actuated by the eccentric 20, which may be adjustable in any well known manner to vary the throw of the arm 19. Through the described operating mechanism, the needle-bar 12 evidently receives endwise reciprocating and laterally vibratory movements, the extent of lateral movement being adjustable. The needle-thread take-up employed may be of any suitable construction and need not be described herein.

Adjacent the eccentric 19 the driving shaft 5 carries a bevel gear 21 meshing with a similar gear 22, carried by the upper end of a vertical, intermediate shaft 23, journaled at its upper end in a bearing provided in a lug 24 upon the standard 2. At its lower end, the shaft 23 is journaled in a bearing

formed in the frame of a housing 26 suitably secured to the bed-plate 1. Within the opening 27 afforded by the frame of the housing 26, the shaft 23 carries a worm 28 and a bevel-gear 29. The worm 28 drives a worm-wheel 30 secured upon a substantially horizontal feed-wheel actuating shaft 31 journaled at its rearward end in a bushing 32 suitably secured in an aperture provided 10 in the frame of the housing 26. The bevel gear 29 meshes with a similar gear 33 carried by the rearward end of the loop-taker actuating shaft 34 journaled in a bushing 35 suitably secured in the housing 26. The 15 opening 27 of the housing 26 may be packed with lubricant and is closed by detachable plates 36 and 37 secured in any suitable manner upon the frame of the housing. The loop-taker actuating shaft 34 extends 20 substantially parallel to the driving shaft 5 and is journaled at its forward end in the bushing 38 secured by set-screw 39 in a suitable aperture provided in a second housing 40. A bevel gear 41 carried by the forward end of the shaft 34 and located in an opening 42 afforded by the housing 40, meshes with a similar gear 43 suitably secured upon a vertical loop-taker carrying shaft 44. The shaft 44 is journaled for rotation in the housing 40 and at its upper end carries a loop-taker 45 of a well known type containing a mass of under thread around which the loop of needle-thread is cast. The bevel gears 41, 43 are of a ratio 25 whereby the vertical loop-taker shaft receives two rotations to one rotation of its driving shaft.

The forward end of the feed-shaft 31 is journaled in the housing 40 and carries a 40 spur-gear 46 meshing with a similar gear 47 from which the feed-wheel 48 derives continuous rotary movements during the operation of the machine. The supporting means for the feed-wheel may be of the 45 same character as that fully described in the prior Patent No. 1,414,625, before referred to, said feed-wheel 48 projecting through a slot in the throat-plate 49 to engage and advance the work. Opposed to the feed- 50 wheel is a roller-presser 50 carried by the lower end of a presser-bar 51, journaled for endwise movement in the head 4 and which presser-bar may be depressed in any suitable manner to cause said roller-presser 50 55 to yieldingly engage the work.

Referring now more particularly to the present improvement, the rear side of the swinging frame 15 is provided with spaced flat-surfaced lugs, as 52, providing slide- 60 ways for the lateral ears as 53, of a trimmer-bar 54, said ears having vertically disposed elongated guide-slots, as 55. The trimmer-bar is guided for endwise reciprocatory movements upon the frame 15 by screws, as 65, passing through the guide-slots 55 and

threaded into the lugs 52, and is further guided by a lateral extension 57 of the frame guide-bracket 58. To the lower end of the trimmer-bar 54 a trimmer-blade 59 of the chop-trimmer type is secured by means of 70 screws, as 60, for lateral adjustment, a finger-piece 61 being suitably secured upon the trimmer-blade to facilitate manual depression of the trimmer-bar into operative position. The trimmer-blade 59 is provided with 75 the usual inclined cutting edge 62 and with the guide-projection 63, the latter in the operative position of the blade entering an elongated slot 64 provided in the throat-plate 49. The blade-edge 62 cooperates with the 80 edge 65 of a defining wall of the slot 64 in the throat-plate, said edge 65 constituting in effect a ledger-blade. A spring-pressed follower 66 pivotally supported on the throat-plate and which may be of any usual form is 85 preferably employed to close the slot 64 in the raised position of the trimmer-blade.

At its upper end, the trimmer-bar 54 has a ball-joint connection 67 with a slide-bar 68, confined to endwise movement in the head 4 and carrying at its upper end a lateral extension 69 overlying a rod 70. The rod 70 is journaled for endwise movement within the hollow upper end of the presser-bar 51 and is normally urged upwardly by a spring 71 within said presser-bar, whereby when the trimmer-bar is disconnected from its actuating mechanism, it is lifted to and yieldingly held in an inoperative position determined by the engagement of the lower ends of the slots 55 with the screws 56.

In order to impart endwise reciprocatory movements to the trimmer-bar 54 upon the vibratory frame 15, said trimmer-bar is provided with a slot 72 adapted to be entered by a roller 73 carried by the free end of an arm 74 extending laterally from one end of a rock-shaft 75. This shaft 75 is journaled for rocking and endwise sliding movements in bearing lugs, as 76, provided on the rear side of the bracket-arm of the machine. Suitably secured upon the rock-shaft 75 is an arm 77 having a fork straddling an eccentric 78 upon the main-shaft 5 of the machine. The rock-shaft 75 may be shifted 115 endwise to connect and disconnect the roller 73 from the trimmer-bar and to this end there is provided a manually operable lever 79, 80 secured upon a fulcrum-pin 81 journaled upon the bracket-arm 3. The arm 79 of said lever extends forwardly underneath the bracket-arm 3 for convenient manipulation thereof, and the other arm 80 of said lever is engaged by a spring 82 functioning to yieldingly maintain connected the trimmer-bar and its reciprocating mechanism. Projecting from the arm 79 of said lever is a forked lug 83 straddling the grooved end of the shaft 75, whereby movements of said lever 79, 80 are transmitted to the rock-shaft. 120

During the endwise movements of the rock-shaft, the forked arm 77 slides upon the eccentric 78 and consequently the shaft 75 is constantly rocking during the operation of 5 the machine regardless of whether or not the trimmer-bar is connected therewith.

The present improvement evidently retains all of the advantages inherent in a trimmer of the reciprocating-blade type and 10 overcomes the difficulty heretofore present in this type of trimmer in that it may effect its work-severing action in unison with the feed of the work by reason of the fact that the trimmer-blade is vibrated laterally during 15 its work-severing action in the direction of movement of the advancing work.

Having thus set forth the nature of the invention, what I claim herein is—

1. In a sewing machine, in combination, 20 stitch-forming mechanism including a reciprocating needle, means for reciprocating said needle, means for continuously feeding the work during the reciprocations of said needle, an endwise reciprocating trimmer-bar, a trimmer-blade carried by the trimmer-bar, and means for reciprocating said trimmer-bar independently of the reciprocations of the needle during the action of said work-feeding means.

30 2. In a sewing machine, the combination with stitch-forming mechanism, work-feeding mechanism including a work-advancing feed-wheel, and means for continuously rotating said feed-wheel to continuously advance the work during the operation of the machine, of an endwise reciprocating trimmer-blade, means for reciprocating said blade to effect a work-severing operation, and means for laterally vibrating said blade 40 in the direction of feed during the work-severing action of said blade.

3. In a sewing machine, the combination with stitch-forming and work-feeding mechanism including an endwise reciprocating needle laterally movable while in the work in the direction of the line of seam-formation, and means for actuating said needle, of a reciprocating trimmer-blade having its cutting edge disposed substantially 50 parallel with the line of seam-formation and laterally movable during its work-severing action in unison with the advance of the work, and means for reciprocating said trimmer-blade.

55 4. In a sewing machine, the combination with stitch-forming and work-feeding mechanism including a work-penetrating endwise-reciprocating needle laterally movable while in the work in the direction of the line of seam-formation, and means for actuating said needle, of a chop-trimmer for severing the work, and means for actuating said trimmer to effect its work-severing action during said lateral movements of the needle.

65 5. In a sewing machine, in combination,

stitch-forming mechanism including a reciprocating needle, means for reciprocating said needle, means for continuously feeding the work during the reciprocations of said needle, a trimmer-blade carrying bar, 70 a vibratory frame upon which said bar is mounted for endwise reciprocation, means for vibrating said frame in the direction of the line of seam-formation, and means for reciprocating said bar upon said frame. 75

6. In a sewing machine, in combination, stitch-forming mechanism including a needle-carrying bar, a vibratory-frame upon which said needle-bar is journaled for endwise reciprocation, means for vibrating said 80 frame, a trimmer-blade carrying bar mounted upon said frame for endwise reciprocation, and means for reciprocating the trimmer-bar.

7. Trimming mechanism for sewing machines comprising a trimmer-blade carrying bar, a vibratory frame upon which said bar is mounted for endwise reciprocation thereupon, means for vibrating said frame in the direction of the line of seam-formation, means for reciprocating said bar upon said frame, and means for throwing said bar into and out of operation independently of the vibratory movements of said frame. 90

8. Trimming mechanism for sewing machines comprising a trimmer-blade carrying bar, a vibratory frame upon which said bar is journaled for endwise reciprocation, means for vibrating said frame in the direction of the line of seam-formation, means for reciprocating said bar upon said frame, and manually controlled means for disconnecting said bar from its reciprocating means during the operation of the machine. 100

9. Trimming mechanism for sewing machines comprising a trimmer-blade carrying bar, a vibratory frame upon which said bar is journaled for endwise reciprocation, means for vibrating said frame in the direction of the line of seam-formation, means for reciprocating said bar upon said frame, manually controlled means for disconnecting said bar from its reciprocating means, and yielding means for shifting the disconnected 110 trimmer-bar into an inoperative position.

10. In a sewing machine, the combination with stitch-forming mechanism, and work-feeding mechanism continuously advancing the work during the operation of the machine, of a trimming mechanism including a trimmer-blade moving laterally during its work-severing action in unison with the advance of the work under the action of said work-feeding mechanism and means for 120 actuating said trimmer-blade.

In testimony whereof, I have signed my name to this specification.

JOHN C. RINGE.
